UNITED STATES PATENT OFFICE.

ROBERT S. MEARS, OF TOPEKA, KANSAS.

GUARD FOR WATER-GAGES.

SPECIFICATION forming part of Letters Patent No. 635,565, dated October 24, 1899.

Application filed June 18, 1898. Serial No. 683,782. (No model.)

To all whom it may concern:

Be it known that I, ROBERT S. MEARS, of Topeka, in the county of Shawnee and State of Kansas, have invented certain new and useful Improvements in Guards for Water-Gages, of which the following is a specification.

My invention relates to that class of apparatus which is used to indicate the level of the water in steam-boilers and which is known technically as a "water-gage," and particularly to the means for protecting an operator from injury due to the explosion and breaking of the glass which forms the gage proper.

The principal object of my invention is to provide simple, economical, and efficient means for protecting an operator from injury due to the bursting of a water-gage glass; and the invention consists in the features, combinations, and details of construction hereinafter described and claimed.

In the accompanying drawings, Figure 1 is a side elevation of a water-gage and guard constructed and arranged in accordance with my improvements; Fig. 2, a rear elevation of the guard removed from the gage; and Figs. 3 and 4 transverse sectional plan views taken on lines 3 and 4 of Fig. 1, looking in the direction of the arrows.

In the art to which this invention relates it is well known that the use of glass water-gages in connection with steam-boilers is essential in order that the fireman and engineer may be informed at all times of the approximate level of the water in the boiler. It is also well known that these "water-glasses," as they are termed, are liable to disruption, and consequently cause explosion, so that oftentimes an operator or other person in the vicinity of these glasses is liable to injury. Especially is this true when such gage-glasses are used in connection with locomotive steam-boilers, where it is absolutely necessary for the engineer and fireman to be at all times in the close vicinity of the glasses, and there have been occasions where serious injury, such as the loss of an eye, has resulted therefrom. It is therefore necessary that some means be provided for protecting the men from injury caused by the bursting of these glasses.

The principal object of my invention, therefore, is to provide a screen-gage for a water-

glass which will enable the engineer and fireman at all times to observe the exact level of the water in the boiler and at the same time protect them from injurious results due to bursting.

Other objects of the invention will appear from an examination of the drawings and the following description and claims.

In using a water-glass gage in connection with my improvements I use the ordinary gage, consisting of two gage-cocks A and A' and which are connected with the water-space of the boiler by means of the threaded ends a and a'. The gage-cocks are provided with stuffing-boxes B and B', between and in which the water-glass C is inserted, so as to prevent it from leaking.

It is well known that it is necessary to provide adjustable holding means to compensate for differences in length and slight differences in diameter of the glasses, and, further, that during adjustments the glass is liable to fracture, and thereby cause explosions. In order to protect the operator from injury during such explosions, I provide a guard and secure it in position as hereinafter described.

To protect the operator, I use a wire-mesh screen-guard D of sufficient open-work for the water-glass to be seen easily through the same. This wire-mesh guard is bent, as shown in Fig. 4, in a U-shaped manner and provided with metallic strips d and d' at the lateral edges and ends, which act to more effectively secure it in place. As shown in Figs. 1 and 2, the guard is bent around the front and side portions of the glass. It is often desirable and necessary that this guard be made and arranged so that it may be adjusted to accommodate the different positions of the glasses. In order to adjustably secure it in position, I provide a metallic base-plate E, arranged at the back of the glass and between the gage-cocks and provide it with supporting stiffening rods or wires e, arranged at the lateral edges of the back plate and projecting from the ends thereof. These rods serve as reinforcements to the back plate and as the means to assist in securing it to the gage. The securing means are of a flexible nature to accommodate the adjustment of the parts and provide for irregularities, and consist of two metallic springs G and G', ar-

ranged at or near each end of the supporting-
5 rods, which have portions g bent around the
threaded portion of the stuffing-boxes, as
shown particularly in Figs. 1 and 3, so that
they may have a slight vertical movement
thereon and at the same time securely hold
all the parts in position.

To secure the parts together, the lateral
strips d of the screen are provided with in-
10 wardly-projecting edges d^2 , as shown particu-
larly in Figs. 2, 3, and 4, and with lugs d^3 ,
both of which parts form channels or recesses
adapted to span the round lateral edges of
15 the back plate, as shown particularly in Figs.
3 and 4. The screen-strips are also provided
with knobs or handles H , arranged in suitable
position to assist in raising or lowering the
parts. The strips d are U-shaped in plan
20 view and, as noted, are formed of metal which
is elastic in its nature and acts as a spring to
hold the lateral edges which contain the an-
gular strips d^2 and lug d^3 in engagement with the
lateral edges of the back plate, so that
25 the knobs H may be grasped and the screen
sprung apart and removed from contact with
the back part, all of which is very simple and
efficient in that this screen can be put in place
or removed without disturbing any of the
other mechanisms.

30 It will be seen from the foregoing descrip-
tion of construction and operation that the
guard may be slipped up and down on the
back plate, so as to permit tightening the nuts
on the glass, without necessitating the re-
35 moval of any portion of the mechanism from
connection with the water-gage. It will also
be seen that the back plate has a slight ver-
tical play, as also have the spring-grips, to
permit of a slight adjustment of the nuts on
40 the stuffing-boxes.

The principal advantages due to the use of
a guard and gage constructed in accordance
with my improvements are that it is simple
to understand, economical to construct, and
45 efficient in use, in that it protects the opera-
tor and at the same time enables him to de-
termine the exact level of the water in the
boiler.

I claim—

50 1. In a water-gage, the combination of a
water-glass, a metallic open-work screen made
from a single continuous piece of material
the full length of the glass and bent to form
a front and sides encircling the front and

sides of the glass, and a back plate having ad-
justably secured thereto the lateral rear edges
of the screen for adjusting the screen in re-
lation to the glass, substantially as described.

2. In a water-gage, the combination of up-
per and lower gage-cocks, and a water-glass
arranged between and inserted in the same,
a guard composed of a portion arranged back
of the water-glass and secured to the gage at
or near each end thereof, a U-shaped screen
bent around the front portion of the gage and
provided with an angular strip at each of its
lateral edges and lugs forming with the an-
gular strip channels to engage with the lat-
eral edges of the back portion, and springs
60 secured to the lateral strips of the screen
for the purpose of holding the screen remov-
ably in engagement with the back plate, sub-
stantially as described.

3. In a water-gage, the combination of a
water-glass, upper and lower gage-cocks be-
75 tween and to which the water-glass is se-
cured, an open-work screen or guard consist-
ing of a single continuous piece of material
the full length of the water-glass, a frame for
the ends and rear edges of the screen or
80 guard, a metallic base-plate at the rear of the
water-glass and located between the gage-
cocks, a spring-clasp at each end of the base-
plate securing the base-plate to the gage and
means for attaching the screen at or near its
85 lateral edges to the base-plate, substantially
as described.

4. In a water-gage, the combination of up-
per and lower gage-cocks, a water-glass lo-
90 cated between the gage-cocks and secured
thereto, a screen or guard consisting of a
single continuous piece of material the full
length of the glass, a frame for the ends and
rear lateral edges of the screen or guard, a
95 base-plate at the rear of the glass and be-
tween the gage-cocks, rod-like projections ex-
tending from each end of the base-plate, a
spring-clasp secured to the rod-like projec-
tions and passing around the gage at or near
100 each gage-cock securing the base-plate to the
gage, and means for adjustably securing the
screen or guard at or near each of its lateral
edges to the base-plate, substantially as de-
scribed.
